UNITED STATES PATENT OFFICE.

FREDERICK W. LOWE, OF PHILADELPHIA, PENNSYLVANIA.

FILE-CUTTING MACHINE.

SPECIFICATION forming part of Letters Patent No. 506,053, dated October 3, 1893.

Application filed April 1, 1893. Serial No. 468,719. (No model.)

To all whom it may concern:

Be it known that I, FREDERICK W. LOWE, of Frankford, in the city and county of Philadelphia and State of Pennsylvania, have invented a new and Improved File-Cutting Machine, of which the following is a full, clear, and exact description.

The object of the invention is to provide a new and improved file cutting machine, which is simple and durable in construction, very effective in operation, and arranged to enable the operator to easily and fully control the several moving devices to produce a proper cut on the file blank.

The invention consists of certain parts and details, and combinations of the same, as will be hereinafter described and then pointed out in the claims.

Reference is to be had to the accompanying drawings, forming a part of this specification, in which similar letters of reference indicate corresponding parts in all the figures.

Figure 1 is a side elevation of the improvement. Fig. 2 is a rear side elevation of the same. Fig. 3 is a cross section of the same on the line 3—3 of Figs. 2 and 6. Fig. 4 is an enlarged cross section of the device for regulating the stroke of the hammer, the section being taken on the line 4—4 of Fig. 2. Fig. 5 is a sectional plan view of part of the same on the line 5—5 of Fig. 4. Fig. 6 is a plan view of the improvement. Fig. 7 is a side elevation of the block frame and carriage with the file blank in position. Fig. 8 is a cross section of the same on the line 8—8 of Fig. 7. Fig. 9 is a similar view of the same on the line 9—9 of Fig. 7. Fig. 10 is an enlarged cross section of the hammer carrying the chisel, the presser foot and adjacent parts, the section being taken on the line 10—10 of Fig. 12. Fig. 11 is a similar view of the same on the line 11—11 of Fig. 12. Fig. 12 is a sectional plan view of same on the line 12—12 of Fig. 2. Fig. 13 is an end elevation of the chisel holder. Fig. 13^a is a side view of part of the same looking in the direction of the arrow 13^a in Fig. 13. Fig. 14 is a sectional plan view of the same on the line 14—14 of Fig. 13. Fig. 15 is an end elevation of part of the intermittent feed mechanism for the carriage; and Fig. 16 is a like view of a modified form of the same.

On the cap plate A' of the column A, is held a swivel block B, in which is mounted to swing into any desired angular position 55 the frame C, carrying a carriage D, receiving an intermittent motion by a suitable mechanism from the main driving shaft E, arranged transversely and journaled in suitable bearings in the frame A², provided with a base 60 A³ secured to the cap plate A', at the rear of the swivel block B.

The main driving shaft E is provided with the usual fast and loose pulleys E', connected by a belt E² with suitable machinery for imparting a continuous rotary motion to the shaft E. The latter is also provided near its rear end with a suitable fly wheel. On the front end of the main driving shaft E is secured a cam I adapted to reciprocate the 70 hammer J fitted to slide vertically in suitable guideways J⁵ held on the frame A², the lower end of the said hammer being provided with a chisel holder J² carrying the chisel J', for cutting the file blank held on the top of the 75 bed D', arranged on the upper surface of the carriage D.

The swivel block B is provided with a central bolt b² which extends through the cap plate A' and the projection A³ and A⁴ formed 80 on the under side of the cap plate A', as plainly shown in Fig. 3. Through the reduced projection A⁴ passes a key b³ also passing through the bolt b² to secure the swivel block in place on the cap plate A'. In the latter screw the 85 set bolts b⁴, engaging with their upper ends the under side of the flange B' of the swivel block B, to hold the latter securely in place to prevent accidental side movement of the block when the machine is in operation. 90

The upper surface of the swivel block B is concaved as at b and on this surface fits the correspondingly-shaped bottom b' of a boss C' forming part of the frame C and projecting downwardly therefrom, as illustrated in Fig. 95 3. The frame C and the boss C' fit between two vertically-extending arms B² of the swivel block B, and on opposite sides of the said frame are formed trunnions d engaging eye bolts d' held in the upper forked end of the 100 arms B² and engaging a partition d², as plainly shown in Figs. 1 and 2, the nuts d³ for the bolts screwing against the under side of the partition d² to securely hold the eye bolts in

place. The axis of the trunnions d forms the center for the segmental contacting surfaces b and b' , so that the frame C can be swung into any angular position, the frame turning 5 on the trunnions d . When the frame is moved into the desired position it is locked in place by screwing up the nuts d^3 , so as to exert a vertical downward pressure on the frame and its boss C', to clamp the latter with its segmental bottom surface b' in contact with the top surface b on the swivel block B. The trunnions d , together with the swivel bolt b^2 are arranged in a vertical plane, passing through the hammer J and the chisel J', so 10 that the several parts mentioned are in alignment with each other, and consequently, the blow of the chisel J' will not tend to loosen the frame C when clamped to the swivel block B, as described.

20 From the arms B^2 of the swivel block B extend horizontally the parallel side bars B^3 connected with each other by a cross bar B^4 at their outer ends, so as to form a guide for the frame C and a support for carrying part 25 of the mechanism F, which serves to impart an intermittent motion to the carriage D held in the trough-like frame C fitted between the said side bars B^3 and the arms B^2 , as plainly shown in the drawings. It is understood that 30 when the swivel block B is turned on the bolt b^2 as a center, then the frame C moves with it, but has an independent adjustment for swinging it into a desired inclined position and locking it therein, as above described.

35 The intermittent feed mechanism F is arranged as follows: On the rear end of the main driving shaft E is secured a crank disk E^3 on which is held adjustably, in a suitable slot e^4 , the wrist pin f^3 connected by a link 40 E^4 with the pawl carrying lever f (see Figs. 1, 2, 6 and 15) fulcrumed on the rear end of the cap plate A'. On the arm f is held a spring pressed pawl f^2 in mesh with a ratchet wheel f' secured on a shaft a^4 journaled in 45 suitable bearings a^2 held on the cap plate A'. On the shaft a^4 is movably arranged a bevel gear wheel a^5 adapted to be secured in place on the said shaft by a set screw or other suitable means and this bevel gear wheel a^5 is in 50 mesh with a bevel gear wheel a^6 secured on the lower end of a hub carrying on its upper end a second bevel gear wheel a^7 and mounted to turn on a stud a^8 secured on a bearing block a^9 held adjustably on a rod a^3 secured 55 to the bearings a^2 of the shaft a^4 . The bearing block a^9 besides carrying the stud a^8 forms a bearing for the shaft a^4 as will be readily understood by reference to Figs. 2 and 3. The block is secured in place on the 60 rod a^3 by a set screw or other means. The upper bevel gear wheel a^7 is in mesh with a bevel gear wheel c' adapted to be secured by a set screw or other means on a shaft c journaled in suitable bearings c^2 projecting from the 65 rear bar B^3 of the swivel block B. The bevel gear wheel a^5 , the block a^9 carrying the dou-

ble bevel gear wheel a^6, a^7 , and the bevel gear wheel c' are held adjustable so as to enable the operator to shift the said gear wheels and block whenever the position of the swivel 70 block B is changed to alter the angle of the cut made by the chisel J', it being understood that whenever the position of the swivel block B is changed the several gear wheels a^5, c', a^6 , and a^7 , must be adjusted to remain in mesh. On the 75 outer end of the shaft c is secured a gear wheel c^3 in mesh with a like gear wheel c^4 fastened on the outer end of a screw shaft c^5 journaled at its outer end in a box c^7 held in the cross bar B^4 connecting the arms B^3 with each 80 other, as previously described. (See Fig. 3.) The other end c^6 of the screw shaft c^5 is journaled in one side of the swivel block B. The screw shaft c^5 is adapted to be engaged by a half nut c^8 mounted to slide on and turning 85 with a shaft c^{10} journaled in the bar B^4 and the swivel block B as plainly illustrated in Fig. 1. See also Figs. 3, 7 and 9. The forward end of this shaft c^{10} carries a handle c^{11} adapted to be taken hold of by the operator so as to turn the said shaft c^{10} to move the half nut c^8 in or out of mesh with the screw shaft c^5 . The half nut c^8 is fitted in a casing c^9 mounted to slide loosely on the shaft c^{10} and the screw shaft c^5 and on the top of 90 this casing is arranged an arm c^{15} adapted to engage a follower D^2 fitted to slide longitudinally in the bottom of the frame C, the said follower being adapted to engage one end of the carriage D, as will be readily understood 95 by reference to Fig. 3. Now, it will be seen that when the shaft E rotates, the crank arm E^3 and link E^4 impart a swinging motion to the pivoted arm f carrying the pawl f^2 so that an intermittent rotary motion is given 100 to the shaft a^4 by the pawl acting on the ratchet f' . The intermittent rotary motion of the shaft a^4 is transmitted by the gear wheel a^5 to the gear wheel a^6 carrying on its hub the second bevel gear wheel a^7 which is 105 thus also rotated. The motion of the gear wheel a^7 is transmitted to the bevel gear wheel c' so that the shaft c receives an intermittent rotary motion and this motion is transmitted by the gear wheels c^3 and c^4 to the 110 screw shaft c^5 . Now, when the half nut c^8 is in mesh with the said screw shaft c^5 at the time the latter has the intermittent rotary motion mentioned, then the casing c^9 is 115 shifted and consequently an intermittent sliding motion is given by the arm c^{15} to the follower D^2 , and thus to the carriage D. The operator, by manipulating the handle c^{11} can, at any time, throw the half nut c^8 out of mesh with the screw shaft c^5 so as to stop the 120 intermittent motion given to the carriage D without stopping the main driving shaft E. 125 In order to impart a vertical reciprocating motion to the hammer J from the main driving shaft E the following device is provided: 13 The cam I on the forward end of the main driving shaft E is engaged on its peripheral

surface by the head i^3 of a screw i^5 screwing in the lower threaded end of a sleeve h (see Fig. 4), fitted to slide vertically in and turning with a sprocket wheel h' journaled in a bracket g secured to the frame A^2 . The sleeve h is provided with a vertically disposed slot engaged by a transversely arranged pin h^2 secured in the hub of the sprocket wheel h' . The lower end of the sleeve h is mounted to turn in an arm i secured by a set screw i' to the stem m of the hammer J . A fixed collar on the sleeve h engages the top of the arm i while a nut i^2 screws on the lower end of the said sleeve h to abut against the under side of the said arm i so that on raising or lowering the latter the sleeve h is likewise raised or lowered, without, however, disengaging the pin h^2 . On the head i^3 of the screw i^5 is secured a pin i^4 arranged parallel to the screw and passing loosely through an aperture in the said arm i . Thus, the screw i^5 is prevented from turning in the sleeve h , but when the latter is rotated by rotating the sprocket wheel h' , the screw i^5 is raised or lowered, caused by the threaded portion of the sleeve engaging the said screw. Over the sprocket wheel h' passes a sprocket chain k also passing over a second sprocket wheel k' secured on a shaft k^2 journaled in the bracket g and provided on its lower end with a hand wheel k^4 under the control of the operator, so that the latter on turning the said hand wheel, can rotate the shaft k^2 , and the sprocket wheel k' , whereby a like motion is transmitted to the sprocket wheel h' by the sprocket chain k . The wheels k' and k^4 are held on the shaft k^2 by nuts k^3 . When the chain k is turned, a rotary motion is given to the sleeve h by the pin h^2 held in the hub of the said sprocket wheel, whereby the screw i^5 is moved up or down to adjust the head i^3 thereof, relative to the cam I , thus regulating the stroke of the hammer J .

It will be seen that when the shaft E is rotated, the cam I moves the head i^3 upward, thus lifting the arm i , the stem m and the hammer J until finally the head i^3 drops off the end of the cam in the recess I' of the same to permit the hammer J to fall. The downward motion of the hammer can be increased or diminished by a spring g^{10} , the tension of which can be increased or diminished by a mechanism presently to be described. On the upper reduced end m' of the shaft m , is held loosely a collar g^{11} on which presses the lower end of the spring g^{10} , engaging at its upper end the collar g^9 forming the head for the screw rod g^{14} screwing in the bevel gear wheel g^8 journaled in a bracket g' secured to the frame A^2 at the upper end thereof. On the head g^9 is also secured a pin g^{12} extending parallel to the screw g^{14} and fitted to slide vertically in an aperture formed in the bracket g' . Thus, the screw rod g^{14} is prevented from turning but when the bevel gear wheel g^8 is rotated, the screw rod is

raised or lowered so as to compress the spring g^{10} or to permit the same to uncoil to reduce the tension according to the direction in which the bevel gear wheel g^8 is rotated. The gear wheel g^8 is in mesh with a bevel gear wheel g^6 held on a shaft g^7 journaled in suitable bearings on the bracket g' and carrying at its outer end a bevel gear wheel g^5 in mesh with a bevel gear wheel g^4 secured on the upper end of a shaft g^2 journaled in suitable bearings in the brackets g and g' . On the lower end of this shaft g^2 is secured a hand wheel g^3 under the control of the operator to enable the latter to conveniently turn the shaft g^2 to rotate the shaft g^7 by means of the gear wheels g^4 and g^5 . The rotary motion of the shaft g^7 causes the gear wheel g^8 to turn as the latter is in mesh with the gear wheel g^6 on the shaft g^7 . Now, by turning the hand wheel g^3 in one direction, the screw rod g^{14} carrying the head g^9 is raised to decrease the tension of the spring g^{10} and when the hand wheel g^3 is turned in the opposite direction, the screw rod g^{14} is caused to move downward so that its head g^9 compresses the spring g^{10} to increase the tension thereof. By this arrangement the blow of the hammer on its downward motion can be increased or diminished to regulate the depth of the cut made on the file blank by the chisel J' .

The chisel holder J^2 carrying the chisel J' is supported on the lower end of the hammer J and is yieldingly mounted as presently to be described, the said holder being shown in detail in Figs. 3, 10, 13, 13^a and 14. The holder J^2 is provided with a recessed body o' in which is fitted the shank of the chisel J' secured in place by a set screw o^2 screwing in a block J^3 held in the horizontally-disposed slide J^4 forming part of the body portion o' , as plainly shown in Fig. 14. The upper end of the body portion is connected by pivots o^3 with the heads o^4 of bolts o^5 extending upwardly through the hammer J , nuts o^6 screwing on the upper end of the said bolts to hold the latter in place in the hammer. The slide J^4 is fitted in the guideways J^5 which also form the guideways for the hammer J . On loosening the bolt o^2 from the chisel shank the block J^3 can be removed from the slide J^4 so as to form an opening in the latter for the convenient removal of the chisel J' in case the latter is to be sharpened or exchanged for a new or different one, as the case may be. Against the rear end of the body o' and near the lower end of the same presses the free end of a spring o^7 secured to the hammer in the rear wall of the recess containing the body o' . (See Fig. 10.) Thus, the body o' has a slight yielding motion laterally, it being understood that the body can swing from the pivots o^3 .

In order to hold the file blank on the bed D' a presser foot o is provided, arranged in an angular position, as indicated in Figs. 3 and 10, the said presser foot engaging the top

of the file blank closest to the cutting edge of the chisel J' . The presser foot o is secured by a screw or other means to the lower end of a presser bar G^2 pivoted on a bolt m' held vertically adjustable in a recess m^6 formed in the arm A^6 projecting from the frame A^2 and carrying the hammer previously described.

- In order to cover the recess m^6 I provide a plate m^5 fitted against one side of the arm A^6 and on which screws the nut of the bolt m' . The upper end of the presser bar G^2 carries a bolt m^4 engaging a segmental slot formed in a slide G fitted to slide vertically in suitable bearings formed on the arm A^2 .

The slide G is pivotally connected by a bolt h^4 with a lever G' pivoted on a bolt h^5 carried by a bracket h^6 held vertically adjustable on the arm A^6 of the frame A^2 ; see Figs. 2 and 12. On the front end of the lever G' hangs a rod s supporting a weight K to press the presser foot o with sufficient force on top of the file blank to hold the latter in place.

The downward motion of the lever G' is limited by a stop bolt n' screwing in a lug n^2 forming part of a slide block H^3 fitted to slide in suitable bearings v formed in the arm A^6 to one side of the hammer J , as plainly shown in Fig. 12. On the front of the slide block H^3 is arranged a flange u adapted to be engaged by a cam t' formed on the pivot end of the lever H fulcrumed on a bolt t fastened to the arm A^6 . The cam t extends about at right angles to the lever H , of which it forms part, and when the said lever is in a vertical position, as illustrated in Fig. 11, then the cam t' extends horizontally and permits the slide block H^3 to pass into a lowermost position. When, however, the lever H is swung into a horizontal position as illustrated in Fig. 1, then the cam acts on the flange u and thus imparts an upward sliding motion to the slide block H^3 which latter, by its bolt or set screw n' , imparts an upward swinging motion to the lever G , so that the presser foot o is raised off the file blank. At the same time, the hammer J is raised by an extension H^2 on an arm H' held adjustably on the slide block H^3 , said extension engaging a lug m^3 formed on the front face of the hammer J . In order to make the arm H' adjustable, I provide the same with a vertically-disposed slot engaged by a bolt n screwing in the block H^3 .

The file blank rests on the bed D' and is adapted to engage with its shank an apertured lug r secured by a screw or other means to the top of the carriage D . The shank is also adapted to engage pins placed on the bed D' near the lower end thereof to engage the curved portion of the widest part of the shank so as to hold the file blank straight on the bed. The under side of the carriage D is curved and fits loosely in the correspondingly-shaped top of the frame C , as illustrated in the drawings particularly with reference to Figs. 8 and 9.

On the upper end of the carriage D is secured a handle D^3 adapted to be taken hold of by the operator so as to turn the carriage D in the frame C according to the shape of the file blank supported on the bed D' . It is understood that this turning of the carriage D is necessary in case semi-circular, circular or other curved forms of file blanks are to be cut.

The operation is as follows: When the several parts are in the position illustrated in Figs. 1, 2, 3 and 6, and a rotary motion is given to the main driving shaft E , then the cam I thereon imparts a lifting motion to the hammer J to raise the cutting edge of the chisel J' a suitable distance above the file blank supported on the bed D' , the latter then being in a lowermost position. As soon as the head i^3 drops off the abrupt end of the cam I then the hammer J slides downward with the force regulated by the tension of the spring g^10 , as previously explained. The hammer J on its downward stroke forces the chisel J' to make the cut on top of the file blank, it being understood that the cut will be diagonal, either to the right or left, according to the position of the frame C , which may be adjusted correspondingly to the right or left, the position to the left being illustrated in Fig. 6. During the next upward stroke of the hammer J , the feed mechanism actuates the screw rod c^5 so that a forward feed is given to the nut c^8 , the casing c^9 , and the arm c^{15} , whereby the follower D^2 is pushed forward in the frame C , and thus a like forward movement is given to the carriage D carrying on its bed D' the file blank. Thus on the next downward stroke of the hammer J the chisel J' again makes a cut, which is parallel to the cut previously made, and the above described operation is repeated until the end of the file blank is reached. When it is desired to make the cross cut on the file blank the operator adjusts the frame C to the right in the manner previously described, and at the same time adjusts the several gear wheels on the shafts a^4 and c to retain the said gear wheels in mesh. At the same time the operator swings the handle c^{11} upward to disengage the nut c^8 from the screw shaft c^5 to permit of sliding the casing c^9 back to its outermost position to permit a downward sliding of the carriage D and follower D^2 to move the upper end of the file back under the chisel J' , the latter, of course, being held in an uppermost position by the operator having previously moved the lever H , into a horizontal position as indicated in Fig. 1, to hold the chisel and presser foot above the file blank. When the adjustment has been made, then the machine is again started and the above described operation is repeated so that parallel cross cuts are made on the top of the file blank relative to the cuts previously made; see Fig. 6. In case a rounded file blank is to be cut then the operator by the handle

D³, turns the carriage D correspondingly, to cause the chisel to strike the file blank at the proper place. The intermediate feeding of the carriage D, however, is the same as above, 5 and the bed is shaped to correspond with the shape of the blank to securely hold the latter in place.

It is understood that when a file has been cut and a new blank is to be inserted, the 10 operator need not stop the driving shaft E, as by the lever H the presser foot and hammer can be set out of action for the time being, and the nut c³ can be disengaged to return the carriage D carrying the file blank 15 to make the exchange of file blanks by manipulating the lever c¹¹. When, however it is desired to stop the machine entirely for changing the position of the frame C, as previously described, when making the second 20 diagonal cut, then the operator shifts a shipper rod e' mounted to slide in suitable bearings and provided with a handle e³, as illustrated in Fig. 2. The shipper rod e' then shifts the belt E² from the fast pulley to the 25 loose pulley on which it remains until the changes are made.

As illustrated in Figs. 3 and 15, a single cam I is used but I may employ a double cam I³, as illustrated in Fig. 16. In this case, 30 I dispense with the mechanism connecting the shaft E with the shaft a⁴ and employ instead thereof, the pulleys M and N secured on the shafts E and a⁴ respectively. A belt O passes over the said pulleys to transmit 35 the rotary motion of the shaft thereof to the shaft a⁴ continuously.

It is understood that with this improved 40 file cutter, perfectly cut files are produced simulating to a great extent, the hand made file. The machine is capable of turning out a large number of files in a comparatively short time, and is perfectly under the control of the operator.

Having thus fully described my invention, I 45 claim as new and desire to secure by Letters Patent—

1. A file cutting machine comprising a horizontally adjustable swivel block, having a concave upper face, a frame mounted to swing 50 in the said swivel block, and having a convex projection on its lower face fitting the said concavity; the axis of the frame being the center of the arc described by said convex and concave faces a carriage having an intermittent sliding motion in the said frame, and a reciprocating hammer adapted to carry 55 the chisel and operating over the said carriage to produce cuts on the file blank, substantially as shown and described.

2. A file cutting machine provided with a 60 hammer having a reciprocating motion, and a chisel holder held on the said hammer and comprising a holder body adapted to receive the chisel and fitted in a recess in the ham- 65 mer, and vertically extending bolts held in the said hammer and pivotally connected at

their heads with the said holder body, substantially as shown and described.

3. A file cutting machine provided with a hammer having a reciprocating motion, and 70 a chisel holder held on the said hammer and comprising a holder body adapted to receive the chisel and fitted in a recess in the hammer, vertically extending bolts held in the said hammer and pivotally connected at their 75 heads with the said holder body, and a spring held on the said hammer and pressing against the said pivoted holder body, substantially as shown and described.

4. A file cutting machine provided with a 80 hammer having a reciprocating motion, and a chisel holder held on the said hammer and comprising a holder body adapted to receive the chisel and fitted in a recess in the hammer, vertically extending bolts held in the 85 said hammer and pivotally connected at their heads with the said holder body, a spring held on the said hammer and pressing against the said pivoted holder body, at its inner side below its pivots, and a block held removably in 90 the front open side of said holder body and carrying a set screw adapted to engage the chisel, substantially as shown and described.

5. In a file cutting machine, the combination with a swivel block provided with eye-bolts, of a frame having trunnions mounted in the said eye-bolts, a carriage fitted to slide and to turn in the said frame, a bed held on the said carriage and adapted to support the file blank, a follower fitted to slide in the said 100 frame and engaging the said carriage at one end thereof, an arm held on a casing mounted to slide and engaging the said follower, a revolute screw shaft, and a half nut held in the said casing and adapted to engage the said 105 screw shaft, substantially as shown and described.

6. In a file cutting machine, the combination with a swivel block provided with eye-bolts, of a frame having trunnions mounted 110 in the said eye-bolts, a carriage fitted to slide and to turn in the said frame, a bed held on the said carriage and adapted to support the file blank, a follower fitted to slide in the said frame and engaging the said carriage at one 115 end thereof, an arm held on a casing mounted to slide and engaging the said follower, a revolute screw shaft, a half nut held in the said casing and adapted to engage the said screw shaft, and means, substantially as shown and 120 described, for swinging the said half nut into or out of contact with the said screw shaft, as set forth.

7. In a file cutting machine, the combination with a shaft, of a bevel gear wheel adjustable thereon, a block mounted to slide on the said shaft and adapted to be locked in place on a suitable rod, the said block carrying a pin, a double bevel gear wheel mounted to turn on the said block-pin and having one 130 of its bevel gear wheels in mesh with the said first-named bevel gear wheel, a second,

- single bevel gear wheel in mesh with the second bevel gear wheel of the double bevel gear wheel, a second shaft on which the said second bevel gear wheel is held adjustably, 5 and a screw shaft geared with the said second shaft, substantially as shown and described.
8. In a file cutting machine, the combination with a shaft, of a bevel gear wheel adjustable thereon, a block mounted to slide on the said shaft and adapted to be locked in place on a suitable rod, the said block carrying a pin, a double bevel gear wheel mounted to turn on the said block pin and having one of its bevel gear wheels in mesh with the said 10 first-named bevel gear wheel, a second, single bevel gear wheel in mesh with the second bevel gear wheel of the double bevel gear wheel, a second shaft on which the said second bevel gear wheel is held adjustably, 15 a screw shaft geared with the said second shaft, and a swivel block provided with an extension frame carrying the said screw shaft and the said second shaft, substantially as shown and described.
- 20 9. In a file cutting machine, the combination with a shaft, of a bevel gear wheel adjustable thereon, a block mounted to slide on the said shaft and adapted to be locked in place on a suitable rod, the said block carrying a pin, a double bevel gear wheel mounted to turn on the said block pin and having one of its bevel gear wheels in mesh with the said 25 first-named bevel gear wheel, a second, single bevel gear wheel in mesh with the second bevel gear wheel of the double bevel gear wheel, a second shaft on which the said second bevel gear wheel is held adjustably, 30 a screw shaft geared with the said second shaft, a swivel block provided with an extension frame carrying the said screw shaft and the said second shaft, substantially as shown and described.
- 35 10. In a file cutting machine, the combination with a shaft, of a bevel gear wheel adjustable thereon, a block mounted to slide on the said shaft and adapted to be locked in place on a suitable rod, the said block carrying a pin, a double bevel gear wheel mounted to turn on the said block pin and having one of its bevel gear wheels in mesh with the said 40 first-named bevel gear wheel, a second, single bevel gear wheel in mesh with the second bevel gear wheel of the double bevel gear wheel, a second shaft on which the said second bevel gear wheel is held adjustably, 45 a screw shaft geared with the said second shaft, a swivel block provided with an extension frame carrying the said screw shaft and the said second shaft, and a carriage adapted to support the file blank, a frame pivoted to the said swivel block and in which the said carriage is fitted to slide, and a half nut engaging the 50 said screw shaft and mounted in a casing and having an arm for shifting the said carriage, substantially as shown and described.
11. In a file cutting machine, the combination with a presser foot held on a pivoted 55 presser bar, of a slide having a segmental slot near its upper end, an adjusting bolt held on the said presser bar, and extending through said segmental slot, a pivot connecting the slide and presser bar below said segmental slot and a lever pivotally connected with the said slide, substantially as shown and described.
12. In a file cutting machine, the combination with a presser foot held on a pivoted 60 presser bar, of a slide having a segmental slot near its upper end engaged by a bolt held on the said presser bar, a pivot bolt connecting said presser bar and slide below said segmental slot and extending through a vertical slot 65 in the frame a lever pivotally connected with the said slide, and a weight held on the said

lever to hold the presser foot forcibly in contact with the file blank, substantially as shown and described.

13. In a file cutting machine, the combination with a hammer mounted to slide and provided with a stem, of a spring pressing on the said stem, a device, substantially as described, for regulating the tension of the said spring, an arm or bracket secured on the said stem, a sleeve mounted in the said bracket, a bolt screwing in the said sleeve and provided with a head adapted to be engaged by a cam, the said head being also provided with a pin loosely engaging the said bracket to prevent turning of the bolt, and means, substantially as described, for imparting a turning motion to the said sleeve to adjust the bolt head relative to said cam, as set forth.

14. In a file cutting machine, the combination with a revoluble cam, of a bolt provided with a head adapted to be engaged by the said cam, a sleeve in which screws the said bolt, a bracket in which the said sleeve is mounted to turn, the said bracket being adapted to be fastened to a hammer stem, a pin projecting from the said bolt head, and extending loosely through the said bracket, and a sprocket wheel mounted to turn and through which passes loosely the said sleeve, the said 95 sprocket wheel carrying a pin engaging a slot in the said sleeve, substantially as shown and described.

15. In a file cutting machine, the combination with a revoluble cam, of a bolt provided with a head adapted to be engaged by the said cam, a sleeve in which screws the said bolt, a bracket in which the said sleeve is mounted to turn, the said bracket being adapted to be fastened to a hammer stem, a pin projecting from the said bolt head and extending loosely through the said bracket, a sprocket wheel mounted to turn and through which passes loosely the said sleeve, the said 100 sprocket wheel carrying a pin engaging a slot in the said sleeve, and means for revolving the said sprocket wheel, to cause vertical adjustment of the said bolt and its head relative to the cam, substantially as shown and described.

16. In a file cutting machine, the combination with a hammer having a reciprocating motion and provided with a chisel holder adapted to carry the chisel, of a slide block having a slotted vertically adjustable arm 105 and a flange, a set screw extending through said slot into the block, and a cam lever adapted to engage the said flange to raise the said block, to move the arm thereon into contact with a projection on the said hammer, substantially as shown and described.

17. In a file cutting machine, the combination with a hammer having a reciprocating motion and provided with a chisel holder adapted to carry the chisel, of a slide block 110 having a slotted vertically adjustable arm and a flange, a set screw extending through

said slot into the block, a cam lever adapted to engage the said flange to raise the said block, to move the arm thereon into contact with a projection on the said hammer, a vertical set screw held on the said slide block, a weighted lever adapted to rest on the said set screw, a slide pivotally connected with

the said lever, and a presser bar connected with the said slide and carrying a presser foot, substantially as shown and described.

FREDERICK W. LOWE.
